UNITED STATES PATENT OFFICE.

WILLIAM G. BENNINGHOFF, OF WILKINSBURG, PENNSYLVANIA.

VALVE.

No. 910,163.

Specification of Letters Patent.

Patented Jan. 18, 1909.

Application filed December 10, 1906, Serial No. 347,075.

To all whom it may concern:

Be it known that I, WILLIAM G. BENNINGHOFF, a citizen of the United States, residing at Wilkinsburg, in the county of Allegheny and State of Pennsylvania, have invented 5 certain new and useful Improvements in Valves, of which the following is a specification, reference being had therein to the accompanying drawing.

10 My invention relates to improvements in valves, particularly hydraulic valves subjected to high pressure, and it has for its object to provide a construction whereby all wear between the moving parts may be compensated for to secure fluid-tight engagement at all times. This object is secured by the construction shown in the accompanying drawings wherein,

Figure 1 is a partial view in side elevation 20 of the upper portion of the valve. Fig. 2 is a vertical sectional view on an enlarged scale showing the valve in position for supplying pressure. Fig. 3 is a cross sectional detail view on the line III. III. of Fig. 2. 25 Fig. 4 is a detail view of the movable element of the valve showing the modified construction of the seat.

In the drawings 2 represents the casing of 30 a reciprocating valve constructed for the purpose of supplying pressure to any point of utilization in one position, and to exhaust therefrom in another position, in the manner well understood with this class of devices.

3 is a reciprocating valve, preferably cylindrical in form, mounted within the vertical cylindrical interior of the casing 2, and provided with a transverse port 4 adapted to register with the supply channels of the valve at each side to accomplish the object 40 desired. The valve 3 is also provided with an exhaust port 5, adapted in the lowered position of the valve as shown to register with the supply passage leading from the source of pressure to the motor, and to permit exhaust therefrom in the raised position, 45 as indicated in dotted lines in Fig. 2.

Ordinarily in valves of this character there is considerable wear on the moving element and the faces with which it makes contact, 50 due to the excessive pressure of the fluid employed, grit, sand, and other impurities, and the objects of my construction are to provide means whereby such wear is compensated. For such purpose I provide one or more relatively movable or "floating" circulation 55 nipples 6, 6, adapted to form continuations

of the main circulation pipes 7, 8, at each side of the valve casing, which pipes are secured into suitable receiving and supply portions as the flanged caps thereof, by screw threads in the usual manner. By this arrangement, the outer ends of one or both of the floating nipples are subjected to the full pressure of the fluid, and are thus constantly pressed inwardly against the face of valve 3 60 at one or both sides. Between said caps and the floating nipples 6 I preferably insert springs 9, 9, of any suitable construction, but preferably helical in form, suitably seated in convenient recesses or bearings on the inner side of the casing walls and bearing inwardly at each side against the outer ends of nipples 6. By this construction, as the inner ends of the nipples are worn away 65 or as the abutting faces of the valve become worn, the nipples will be automatically and constantly adjusted to make a tight bearing therewith, thereby absolutely preventing any leakage.

The nipples are preferably mounted within 70 packing boxes formed in the casing whereby packing 10 of leather disks or other suitable material may be adjusted around the nipples by means of followers 11 and adjusting nuts 12 threaded in the interior of the casing, as clearly shown. Any other suitable 75 packing mechanism may be employed if desired, and as thus constructed a completely fluid-tight arrangement is provided.

For the purpose of lubricating the valve 3 80 I provide one or more oil channels 13, surrounding the upper and lower or either of the inner faces of the vertical slide-way for the valve 5, whereby said valve is embraced at all times by streams of oil, furnished from 85 the exterior through lateral openings 14 from an oil cup or in any other manner desired.

The valve 3 is raised and lowered by 90 means of a lever 15 connected by stem 16 100 passing through cap 17 or other suitable construction at the upper end of the valve casing, the lever 15 being pivotally mounted at 18 in an upwardly disposed post extension 19 of one of the valve casing caps. By this 105 or any other suitable arrangement the valve 3 is located in its desired position for supply or exhaust respectively.

In Fig. 4 I have shown a modified construction of valve 3' having the ports 4' and 110 5', the surrounding bearing face of said valve adjacent to such ports being bounded

within a groove or recess 20, limiting at its top, bottom and sides the sliding face with respect to the nipple 6, by which construction it will be seen that the sliding face of the valve with respect to said nipples is terminated by shoulders whereby the wear will be even throughout and a fin or terminal ridge avoided, thus insuring good contact at all times.

10 It will be understood that various changes or modifications may be made in the design, construction or arrangement by the skilled mechanic, but all such changes are to be considered as within the scope of the following claims.

What I claim is:

1. In a valve, the combination of a casing, a slidably mounted ported valve therein, floating circulation nipples slidably mounted in the casing arranged to abut against the valve and to furnish circulation therethrough, outer caps secured to the casing provided with circulation connections and inlet and outlet apertures in alinement with the floating nipples, said caps being provided with spring-bearing recesses, and spiral springs inserted between the caps and the ends of the nipples arranged to press them inwardly against the ported valve and to provide an interior circulation space, substantially as set forth.

2. In a valve, the combination of a casing, a slidably mounted ported valve therein, floating circulation nipples slidably mounted

ed in the casing arranged to abut against the valve and to furnish circulation therethrough, means for packing said nipples, outer caps secured to the casing provided with circulation connections and inlet and outlet apertures in alinement with the floating nipples, said caps being provided with spring-bearing recesses, and spiral springs inserted between the caps and the ends of the nipples arranged to press them inwardly against the ported valve and to provide an interior circulation space, substantially as set forth.

3. In a valve, the combination of a cylindrical casing having oppositely arranged connecting portions with hollow interiors leading to the interior of the casing, a slidably mounted ported valve within the casing, floating circulation nipples mounted within the connecting portions, packing devices surrounding the nipples within said connecting portions, outer caps secured on said portions provided with fluid circulation connections and inner spring seats, and springs inserted between said seats and the ends of the circulation nipples arranged to press the nipples inwardly against the ported valve, substantially as set forth.

In testimony whereof I affix my signature in presence of two witnesses.

WILLIAM G. BENNINGHOFF.
